United States Patent Office.

WILLIAM MOSES, OF BUFFALO, NEW YORK.

Letters Patent No. 81,668, dated September 1, 1868.

IMPROVEMENT IN STEAM-GENERATORS.

The Schedule referred to in these Letters Patent and making part of the same.

TO ALL WHOM IT MAY CONCERN:

Be it known that I, WILLIAM MOSES, of the city of Buffalo, county of Erie, and State of New York, have invented certain Improvements in Steam-Boilers; and I do hereby declare that the following is a full, clear, and exact description thereof, reference being had to the accompanying drawings, making a part of this specification.

The nature of my invention consists in the construction of the auxiliary steam-generating vessels with a contracted shank, through which pass an induction-pipe and eduction-orifice, so that they may be attached by said shank to the crown-sheet or sides of the boiler-furnace, and brought into communication with the water-space of the boiler, whereby a great addition to the effective heating-surface results, without materially affecting the strength of said crown-sheet and sides.

In the accompanying drawings—

Figure I is a sectional view of auxiliary steam-generating vessel as constructed for application to the crown-sheet of the furnace, the section being taken through the connecting-shank.

Figure II is a sectional view of same taken at right angles to Fig. I.

Figure III is a sectional view of an auxiliary steam-generating vessel as constructed for application to the sides of the furnace, the section being taken through the connecting-shank.

Figure IV is a sectional view of same taken at right angles to Fig. III.

Figure V is a longitudinal sectional elevation of a common return-flue boiler, showing the application of my auxiliary steam-generating vessels thereto.

Figure VI is a cross sectional elevation thereof through the furnace.

Figure VII is a cross sectional elevation thereof through the return-chamber.

In Figs. I and II, A represents the auxiliary steam-generating vessel, made of cast iron, in the form of a hollow sphere, and provided at one side with a hollow radial shank, A¹, of a diameter greatly reduced from that of the sphere. Into this shank is inserted a screw-thimble, A², of wrought iron, which forms a part of the shank, and serves to connect the generating-vessel to the crown-sheet B by being screwed therein, as represented. The necessary screw-thread to make this connection might be cut directly upon the cast shank A¹, but, to obtain equal strength, would require to be of larger diameter, and hence would require a larger hole to be tapped in the crown-sheet for its reception, thereby reducing to a greater extent the strength of the crown-sheet—a result to be avoided as far as possible.

C represents the induction-tube inserted through the bore of the shank A¹, and reaching down to nearly the bottom of the sphere, it being supported in position by the bridge C', cast with the sphere.

D represents the eduction-orifice, formed by making the diameter of the induction-tube less than the bore of the shank A¹. The office of the induction-pipe and eduction-orifice is to produce a circulation of water through the vessel, and carry off the steam generated, as will be hereinafter more fully described.

In Figs. III and IV, A represents the generating-vessel, and A¹ its shank, which is cast tangentially thereon instead of radially, to adapt it for connection to a vertical plate, such as form the sides of the fire-box. The shank has a screw-thread cut thereon, so that it may be screwed into the side plate B, and is further provided with a jam-nut, B¹, and shoulder, B², to give additional security to the connection.

The tapping of the hole in the boiler-plate may be dispensed with, and the jam-nut and shoulder depended upon for making the connection, which plan will have the advantage of allowing the generating-vessels to be placed in closer proximity with each other, by avoiding the necessity of turning them around the axis of the shank, the eccentric position of which would require a considerable space for such movement.

C represents the induction-pipe entering through the shank A¹, and reaching, by a right-angle bend, to nearly the bottom of the generating-vessel. In cross-section, this pipe is semi-cylindrical, so that in its passage through the shank a corresponding semi-cylindrical eduction-orifice, C', is formed.

The generating-vessel, shank, and induction-pipe are all cast together, as being the most convenient mode of manufacture.

In Figs. V, VI, and VII, A represents a return-flue boiler, of common construction, the fire-box being shown at B, and the return-chamber at C.

E represents the steam-generating vessels as secured to the crown-sheets by their shanks, E¹, and pendent therefrom, and being made of such dimensions as not to trench upon the necessary fuel-space.

E² represents the same as connected, by their shanks, E², to the vertical sides of the fire-box.

F represents a similar application to the sides and top of the return-chamber C.

The operation of the auxiliary generators may be briefly stated, as follows:

Being, from their connection with the water-space of the boiler, necessarily filled with water, the same, as it is converted into steam by the heat from the fire, will pass out through the eduction-passages into the steam-room, and its place will be supplied by the entrance of new water, through the induction-pipes, under a well-known law of circulation. The large quantity of surface exposed to the fire by the generators, and the small volume of water contained therein, will render the generation of steam therein exceedingly rapid.

The addition to the heating-surface of the boiler is further attained at a most desirable point, as the generators are exposed to the direct heat of the fire, thereby rendering them much more efficient than the flues.

The manner of connecting the generators by the contracted shank removes all practical difficulty in their application, since secure joints may be made without reducing the strength of the crown-sheet and sides materially.

By making the dimensions of induction-pipe and eduction-orifice no larger than absolutely requisite to establish the circulation, and the diameter of the spheres as large as the spare depth in the fire-box will permit, the maximum of heating-surface, with the minimum of injury to the strength of the crown-sheet, will be obtained, and it is in the accomplishment of this desirable result that the merit of the invention lies.

I am aware of the inventions of E. L. Hutchinson, and that of Edwin Reynolds, patented respectively October 9, 1866, and April 4, 1865, and do not claim any of the features set forth or described in said patents.

What I claim as my invention, and desire to secure by Letters Patent, is—

The auxiliary steam-generating vessels, when constructed with contracted shanks, and induction and eduction-orifices, and applied to the crown-sheet and sides of a boiler, substantially as herein set forth.

WILLIAM MOSES.
